(57) **CLAIM**

The ornamental design for a camera, as shown and described.

DESCRIPTION

FIG. 1 is a front view of a camera with a closed housing showing my design;

FIG. 2 is a rear view thereof;

FIG. 3 is a first side view thereof;

FIG. 4 is an opposing side view thereof;

FIG. 5 is a bottom view thereof;

FIG. 6 is a top view thereof;

FIG. 7 is a rear perspective view thereof;

FIG. 8 is a front view of the camera of FIG. 1 with an opened housing;

FIG. 9 is a rear view thereof;

FIG. 10 is a first side view thereof;

FIG. 11 is an opposing side view thereof;

FIG. 12 is a bottom view thereof;

FIG. 13 is a top view thereof; and,

FIG. 14 is a front perspective view thereof.

The portions of the camera in broken lines illustrating additional features are for environmental purposes only and form no part of the claimed design.
